MAGAZINE PENCIL.

Application filed June 12, 1926, Serial No. 115,685, and in Germany May 4, 1925.

The present invention relates to a lead-pencil of the type in which a movable magazine tube carrying a number of sticks of lead, adapted to be automatically fed, one at 5 the time, to a reciprocating lead carrying member is pressed forwardly by hand and returned by a spring, to impart a step by step forward feed to the lead.

In describing the invention in detail, reference will be had to the accompanying drawing, forming part of the specification, and wherein like characters denote corresponding parts in the several views, in which:

15 Fig. 1 shows a central vertical section through the lead pencil in the position for use,

Fig. 2 shows a corresponding view of the pencil the lead carrying member, which is 20 shown in elevation, being pushed forward, and

Fig. 3 is a similar view to Fig. 2, but with a somewhat modified form of the lead carrying member.

25 The interior mechanism of the pencil consists essentially of a stationary sleeve *a*, a magazine-tube *b* sliding therein and carrying a tubular lead propeller *e*, a coiled spring *d* disposed between a ring *h* fixed in 30 the sleeve *a* and the lower end of the magazine-tube *b*, as well as a tube or guide *f* for the lead with a hat-shaped spreading member *i* for the lead propeller *e*, loosely mounted thereon. The lower end of the stationary 35 sleeve *a* is bent inwardly to form a shoulder *a'*. The lower part of the tubular lead propeller *e* is split, forming spring arms for engaging and gripping the lead.

The whole mechanism is held in known 40 manner in a shell or holder *k* which terminates at its lower end in a point or tip *g*. The movable magazine-tube *b*, which as well as for operating the mechanism at the same time serves as a magazine for spare leads is 45 normally retained by the spring *d* in the position indicated in Fig. 1. The tubular lead propeller *e* situated on the lower end of the magazine-tube *b* serves for engaging and moving the leads *c* which fall into it 50 from the magazine-tube *b*. These are caught in the restricted part *e''* of the propeller and from there are advanced through the guide tube *f* into the tip *g* in the following manner.

55 By the pressure of the spring *d* upon the magazine-tube *b* the widened part *e'* of the

propeller is drawn into the ring *h* fixed in sleeve *a*, which has the result that the part *e''* of the propeller clamps the lead tightly. If the magazine-tube *b* is pressed by the 60 finger into the holder, and therewith the propeller portion *e'* out of the ring *h* then first the strong clamping action of the propeller arms is relaxed and the lead, which thereupon is only held by the mere resilience of the 65 latter, is pushed forward a certain distance through the guide *f* and tip *g*. Upon pressing the magazine-tube *b* further into the holder, the cupped end of the propeller *e* engages over the hat-shaped member *i* (see 70 Fig. 2) on the guide tube *f*, whereby the propeller arms are spread apart and so release the lead *c*. The lead is now held in its advanced position by the clamping action of the tip *g*, so that if the pressure on the 75 magazine-tube *b* is released and this is returned by the spring *d*, the propeller *e* does not take the lead with it. Only when the spreading member *i* strikes with its rim against the shoulder *a'* of the stationary 80 sleeve *a*, thereby being disengaged from the propeller *e*, the propeller arms again grip the lead which is then so firmly clamped by the withdrawal of the propeller portion *e'* into the ring *h* that in writing it does not 85 give away.

By the movement of the magazine-tube in the holder and the resultant alternate opening and closing of the propeller as it is moved to and fro, the lead is intermittently 90 advanced a short distance.

Whilst in the practical embodiment according to Figs. 1 and 2 the propeller *e* has a special enlargement at its central portion for withdrawal into the clamping ring *h*, in 95 the modified construction shown in Fig. 3 the cupped end or head of the propeller is adapted to be drawn into a ring *h*, which in this case is somewhat lower in the stationary sleeve *a*. A special enlargement of the propeller is thereby obviated and moreover a longer length of spring *d* is obtained, which is advantageous for smoother working of the tube *b*.

Having now particularly described and 105 ascertained the nature of my said invention, and in what manner the same is to be performed, I declare that what I claim is:

A magazine pencil of the type described, comprising a movable tube the upper part 110 of which is enlarged to serve as magazine for the leads, whilst the lower end is pro-

vided with a split tube of smaller diameter, having an enlargement on the split portion and serving as lead propeller when the magazine tube is pressed into the holder, a 5 ring or annular member fixed in the stationary sleeve of the pencil, the opening in which is smaller than the outside diameter of the said enlarged portion of the split tube or propeller a coil spring located between 10 the ring and the base of the magazine por-

tion of the movable tube to hold the propeller in the upper position thereby forcing the enlarged portion of the latter into the ring, a cap or hat-shaped spreading member for the lead propeller to release the lead after 15 the forward movement and a shoulder to disengage the spreading member from the lead propeller, substantially as described and for the purpose set forth.

HEINRICH MORLOCK.
